UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

SPINDLE-BRAKE FOR SPINNING OR TWISTING APPARATUS.

977,751.

Specification of Letters Patent.

Patented Dec. 6, 1910.

Original application filed December 12, 1908, Serial No. 467,252. Divided and this application filed March 12, 1910. Serial No. 548,909.

To all whom it may concern:

Be it known that I, ALONZO E. RHOADES, a citizen of the United States, and resident of Hopedale, county of Worcester, State of Massachusetts, have invented an Improvement in Spindle-Brakes for Yarn Spinning or Twisting Apparatus, of which the following description, in connection with the accompanying drawing, is a specification, like characters on the drawing representing like parts.

This invention relates to apparatus for spinning or twisting yarn, and it has for its particular object the production of novel and efficient means for stopping the rotation of a spindle when so desired, this application being a division of an application Serial No. 467,252 filed by me the 12th day of December, 1908.

When an end breaks the corresponding spindle must be stopped while the end is pieced up, and such stoppage is effected by a spindle brake adapted to be actuated by the knee of the attendant, thereby leaving the hands free. The ordinary spindle brake is so constructed that oil from the spindle bearing frequently trickles down onto the face of the knee-plate of the brake, so that the clothing of the attendant gets very oily and dirty by the operation of the brake, making this feature of spinning or twisting apparatus very objectionable and disagreeable. In my present invention I have so constructed the spindle brake that the oil cannot collect on the face of the knee-plate, and the objections above mentioned are wholly obviated.

The various novel features of my invention will be fully described in the subjoined specification and particularly pointed out in the following claims.

Figure 1 is a front elevation of a sufficient portion of a twister to be understood, with a spindle brake embodying my invention applied thereto; Fig. 2 is a side elevation of the spindle brake and some of the parts shown in Fig. 1, other parts being shown in cross-section; Fig. 3 is an enlarged front view of the spindle brake, detached; Fig. 4 is a rear view of a portion of the brake, showing the oil catcher; Fig. 5 is a sectional detail on the line 5—5, Fig. 4.

In Figs. 1 and 2 the rotatable spindle A, spindle-rail B, and the vertically-reciprocating

ring-rail C having a ring D for each spindle, may be and are all of usual or well known construction, the spindle having a suitable band-whirl E by means of which the spindle is rotated, it being understood that the spindles are arranged in series, as is customary, and each spindle is provided with a brake.

As herein shown the upturned arm 1 of the brake is provided with a friction-pad 2 adapted to bear against the spindle above the whirl and thereby stop rotation, and the seat 3 which rests upon the top of the spindle-rail B is made open to loosely embrace the base of the spindle-bearing, and the bifurcated leg 4 depends from the seat 3 at its front, terminating in a broad and flat knee-plate 5, such parts of the brake being substantially of usual construction, except that herein the lower end of the leg is turned forward, at 6, where it joins the knee-plate. I have also rearwardly beveled the upper edge of the plate, as at 7, Fig. 5, and the bottom of the opening in the leg extends below the upper edge of the plate, as at 8, and a vertical rib 9 is formed on the back of the plate, as a continuation of the bottom of the leg, said rib terminating in a point 10. Any oil collecting on the brake will sooner or later trickle down the leg 4, and if on the back thereof will run down the rib 9 and drop to the floor off the point 10, and if the oil traverses the front of the leg it meets the beveled edge 7 of the knee-plate, and collects in the depression 8, traveling thence over the back of the leg below the depression and off along the rib 9 as before. As the front face of the knee-plate is offset from the front of the leg it will be manifest that the collected oil cannot in any case travel onto the front of the plate, and therefore the front face will always be kept clean and wholly free from oil. I thus obviate the objections heretofore noted and prevent the transfer of oil to the clothing or person of the attendant.

As shown best in Fig. 3 the upper edge of the knee-plate is made slightly concave from one to the other end, this curvature assisting in directing the travel of the oil to the central depression 8 behind the plate.

The construction of the brake is simple, it is efficient in operation, and is clean and free from oil at all times, preventing any soiling

of the clothing of the attendant when operating the brake.

Having fully described my invention, what I claim as new and desire to secure by Letters Patent is:—

1. In apparatus of the class described, a spindle-rail, a spindle rotatably mounted thereon, a spindle-brake seated on the rail and having an integral leg depending in front of and below the rail and provided at its lower end with an actuating plate, and means on said plate and leg to direct oil from the spindle to the back of the plate and thereby prevent the oil from collecting on the face of the plate.

2. In apparatus of the class described, a spindle-rail, a spindle rotatably mounted thereon, a spindle-brake seated on the rail and having a leg depending in front of and below the rail and provided with a knee-plate set forward from the leg and beveled rearwardly at its upper edge, the leg having a depression therein behind and below the

beveled edge of the knee-plate, to collect oil accumulating on the leg and prevent its passage to the front of the plate.

3. In apparatus of the class described, a spindle-rail, a spindle rotatably mounted thereon, a spindle-brake seated on the rail and having a leg depending in front of and below the rail and provided with a knee-plate set forward from the leg and beveled rearwardly at its upper edge, the leg having a depression therein behind and below such edge, to receive oil collecting on the leg, and a rib on the back of the plate communicating with the end of the leg, to direct oil from said depression and discharge it at the lower edge of the knee-plate at its back.

In testimony whereof, I have signed my name to this specification, in the presence of two subscribing witnesses.

ALONZO E. RHOADES.
